SOAPHOLDER

Roy Aitken, Glasgow, Scotland

Application May 18, 1950, Serial No. 10,018
In Great Britain December 5, 1949

Term of patent 14 years

(Cl. D4—3)

To all whom it may concern:

Be it known that I, Roy Aitken, a British subject and a resident of Glasgow, Scotland, have invented a new, original, and ornamental Design for a Soap Holder, of which the following is a specification, reference being had to the accompanying drawing, forming part thereof.

Fig. 1 is a perspective view of a soapholder showing my new design;

Fig. 2 is a bottom plan view;

Fig. 3 is a sectional view thereof taken on the line III—III of Fig. 2; and

Fig. 4 is a rear elevational view.

I claim:

The ornamental design for a soap holder, as shown.

ROY AITKEN.
